UNITED STATES PATENT OFFICE.

HARRY CARROLL MERRIAM, OF DETROIT, MICHIGAN

CARBURETER.

1,187,463.

Specification of Letters Patent. Patented June 13, 1916.

Application filed July 16, 1915. Serial No. 40,203.

To all whom it may concern:

Be it known that I, HARRY C. MERRIAM, a citizen of the United States, and a resident of Detroit, in the county of Wayne and State of Michigan, have invented certain new and useful Improvements in Carbureters, of which the following is a specification.

In the use of carbureters now known to me, in connection with internal combustion engines, no arbitrary control of the fuel mixture delivered to the engine has been possible to meet engine demands due to variations in temperature, and it was in order to provide such control that my invention was conceived, this referring not alone to the quantity of the mixture but also to the character thereof, in order that the engine will be neither choked nor starved.

A further object of my invention is to provide means for insuring the vaporizing or atomizing of the fuel, whereby air is readily mixed therewith and perfect combustion thereof results, with the consequent economy of engine operation, maximum engine efficiency at each speed, and practical elimination of soot deposit in the cylinders of the engine.

My invention is fully described in the following specification, of which the accompanying drawings form a part, in which like characters refer to like parts in each of the views, and in which:

Figure 1 is an elevation of a carbureter constructed in accordance with my invention; Fig. 2 is a section taken on the line 2—2 of Fig. 1; Fig. 3 is a section taken on the line 3—3 of Fig. 2; Fig. 4 is a section taken on the line 4—4 of Fig. 2; Fig. 5 is an unrolled development of one of two rollers 35 which I employ; and Fig. 6 is a side view of one form of valve control in operative juxtaposition with a thermometer.

In the drawings forming a part of this application I have shown a casing 7 provided with a float chamber 8, having the usual or any desired float 9 therein, and a carbureting chamber 10 in communication with the outer air by means of a pipe 11 and with the engine, not shown, by means of a pipe 12 leading to the manifold intake. A butterfly valve 13 is arranged in the latter pipe and operable by means of a shaft 14 carrying a crank-arm 15 on one end exterior of the casing and pipe 12, in turn connected with a lever 16 by means of a link 17 and which lever is adapted to be connected with the

throttle lever, not shown, as on the steering column of an automobile. A tube 18 leads from the float chamber 8 to the carbureting chamber 10 through the medium of a plurality of nozzles 19, 20, and 21, any desired number of which may be employed. These nozzles are provided with valves 19^a, 20^a, and 21^a, respectively, shown as of the needle type, in pivotal connection with corresponding levers 19^b, 20^b and 21^b, in turn pivoted at 22 to a vertically adjustable plate 23, as clearly shown in Figs. 2 and 6.

The casing is provided with a partition 24 slotted to serve as a guide for the levers 25 passed therethrough, thereby maintaining the needle valves in register with the respective nozzles. The vertically movable plate 23 is connected, as by a link 25, with a lever 26 linked to a lever 27 pivoted at 28 and provided with a slot 29 adjacent its outer end through which readings may be taken of a thermometer 30 arranged beneath said slot and preferably of segmental form on an arc of a circle having the pivot 28 as its center. The outer ends of the valve levers 19^b, 20^b, and 21^b, are normally held in lowermost positions against a portion 31 of the casing casting by means of springs 32, thus forcing the needle valves into the respective nozzles 33 to prevent the passage of fuel but, when said levers are simultaneously raised, the fuel may be drawn through said nozzles in the degree of needle valve movement.

Journaled in the casing, by means of trunnions 33 and 34 indicated by dotted lines in Fig. 2, are two rollers 35 and 36 in close relationship with the three nozzles shown and with each other, these rollers having, each, a portion of the periphery thereof concentric with the axis of the journals thereof, as shown at 37, and being also provided, each, with a series of grooves 38, 39, and 40 in the periphery thereof to present a cam appearance on a section taken through the rollers in the positions of said grooves. The groove 38 is longer than the others, the groove 40 being the shortest, and the groove 39 of intermediate length, as is clearly shown in the plane view of one roller periphery in Fig. 5, this variation in lengths constituting an important feature in the control of the carbureter. Each of these grooves, the sides of which are parallel, is continued to form a portion 41 with converging sides and which, in turn, is continued to form a relatively narrow portion 42 with parallel

sides and of a width approximating the diameter of the nozzles and in the positions of the respective ones of which said grooves are located. The trunnions 33 and 34 carry en- 5 meshed segmental gears 43 and 44 in order to insure complementary roller revolution, this being accomplished by means of the lever 16 which is keyed on the trunnion 34, whereby the rollers and the butterfly valve 10 are simultaneously actuated by the throttle lever on the steering column of an automobile, not shown.

The needle levers 19^b, 20^b, and 21^b are each provided with legs 45, only one of which is shown, carrying rollers 46 on their lower ends bearing on the roller 36, the levers thus being fulcrumed on the ridge 31 for movement by means of the plate 23 when the said plate is raised and when said legs are raised 20 in a manner later explained, and being fulcrumed on said legs when said plate 23 is moved downwardly, the needle valves being thus raised in either event.

The roller 36 is provided with cams 47, 48, 25 and 49, the first of which is the longest and is located on the longitudinal central line of the groove 38, the last of which is the shortest and is similarly arranged with respect to the groove 40, and the second of 30 which is of intermediate length and is located in line with the groove 39, as clearly shown in Fig. 5, and these cams are likewise arranged in line with the respective rollers 46 to raise or lower the respective needle 35 levers. The needle levers are collectively moved by the lever 27 but are individually movable by means of the cams 47, 48 and 49, thereby actuating the respective needle valves accordingly.

40 With the rollers in the initial positions shown in Fig. 2 the concentric portions bear against the pointed sides of the needle valves, and the narrowest portions of the grooves at the pointed ends thereof bear 45 against the sides of the respective nozzles, thus preventing air from passing upwardly at the sides of said nozzles and, if the needle valves be raised at this time, only oil will be drawn out of the nozzles by the suction of 50 the engine. If, however, the valves should be raised at this time, the butterfly valve in the pipe 12 will prevent any such suction in view of the fact that said butterfly valve is closed with the rollers in the positions 55 shown. When the lever 16 is moved to re- 60 solve the rollers in the directions of the arrows, the tapered portion 41 of the groove 38 provides an air passage along the side of the nozzle 19 of a size determined by the de- 65 gree of roller revolution and the butterfly valve 13 is partially opened to the engine, thus allowing air to be drawn into the carbureting chamber in a relatively small quantity. As this roller revolution occurs, the 70 cam 47 slightly raises the lever 19^b and the

needle valve 19^a, thus admitting fuel to the carbureting chamber, which fuel mixes with the air passing upwardly around the nozzle 19 and the mixture is drawn toward the engine. Still further revolution of the rollers 75 opens the groove 38 to its limit and carries the tapered portion of the groove 39 to the position of the nozzle 20 and the cam 48 to a point beneath the roller of the needle lever 20^b, thus raising the needle valve 20^a, this being in the degree of roller revolution, and it will thus be seen that one nozzle is delivering its maximum air and some fuel to the carbureting chamber, and one nozzle is delivering a partial air supply with a fuel supply 80 determined by the degree of adjustment of the parts. Still further revolution of the rollers causes full air supply at two nozzles and some fuel therefrom, and a partial air supply at the nozzle 21 determined by the 85 relative position of the tapered portion of the groove 40 with respect thereto, together with a fuel supply at the last named nozzle determined by the position of the cam 49 with respect to the roller of the needle lever 90 21^b, and when the roller revolution has reached its limit a full air supply is being delivered at all the nozzles, and as much fuel as may pass the needle valves in the adjusted positions due to the cams 47, 48, and 95 49. The butterfly valve 13 is now fully opened and the needle levers are in the positions indicated by dotted lines in Fig. 2, the lever 27 being at this time set at 100 degrees F., a temperature at which the fuel 100 readily vaporizes and mixes with the air, and the engine is running at maximum efficiency, but under the control of the lever 16 and its connected lever, not shown. If, now, the temperature should drop to 60 degrees 105 F., more fuel will be required, in other words the mixture will need to be enriched correspondingly and, if the lever 27 be moved into register with 60 on the thermometer, the plate 23 is depressed and the 110 needle levers are collectively raised to raise all the needle valves in unison, regardless of their individual adjustment by means of the cams or the freedom from the cams, and a corresponding increase in fuel is provided. 115 This is true of any of the possible adjustments, to the different degrees of heat as registered by the thermometer, of the lever 27, and it will thus be seen that I may adjust each of a plurality of valves individually and successively for fuel supply 120 and at the same time adjust the rollers to an air supply for each nozzle individually and successively, from the steering column in the normal operation of an automobile, to vary 125 the quantity of mixture supplied to the engine, and to also at will vary the quality of the mixture to enrich or impoverish the same according to climatic conditions, these results being obtained from a plurality of nozzles 130.

which insure more complete vaporization or atomization according to the number thereof employed.

Aside from the duplication or multiplication of the nozzles and valves therefor and the grooved rollers for controlling the air supply carrying the cams for controlling the fuel supply valves, the details shown and described may be materially modified and still be within the scope of the following claims and within the spirit of my invention. The specific type of nozzles, of valves, and of connections with the manually actuated levers, are unimportant and may be altered to meet varying conditions and to conform to different types of automobiles, boats, and air-craft, my main intent being to supply fuel from one nozzle and air around the same for one demand of the engine, from two nozzles for another demand, for another demand three nozzles, and so on, in the normal operation of an engine, and to be enabled to control all of said nozzles collectively to meet varying conditions due to climatic changes.

An advantage possessed by my carbureter lies in the ability to run the engine from one nozzle and positively control the fuel and air supply therefrom and, when the engine tends to suck the oil through the nozzle in excess quantity for the mixture desired, another nozzle may be brought into operation, and upon demand still another nozzle, and so on, the relative quantities of fuel and air being constant at all the nozzles in any adjustment of the rollers except with the nozzles entirely throttled, this not only tends to economy in the fuel, but insures maximum efficiency under all conditions because of the proper mixture supplied thereto, and also avoids the sooting of the cylinders common to present carbureters.

Having fully described my invention, what I claim as new, and desire to secure by Letters Patent, is:—

1. A carbureter, comprising a fuel supply, a plurality of nozzles in communication therewith, a valve for each nozzle, a roller on each side of said nozzles provided with a groove closely fitting the respective nozzle to prevent the passage of air, said grooves being widened for a desired portion of their lengths, means for revolving said rollers to bring desired portions of said grooves adjacent said nozzles to control the passage of air between said nozzles and rollers, and means for actuating said valves individually.

2. A carbureter, comprising a fuel supply, a plurality of nozzles in communication therewith, a valve for each nozzle, a roller on each side of said nozzles provided with a groove closely fitting the respective nozzle to prevent the passage of air, said grooves being widened for a desired portion

of their lengths, means for bringing the widened portions of said grooves adjacent the respective nozzles individually and successively to control the passage of air between said rollers and the respective nozzles, and means for actuating said valves individually.

3. A carbureter, comprising a fuel supply, a plurality of nozzles in communication therewith, a valve for each nozzle, a roller on each side of said nozzles provided with a groove closely fitting the respective nozzle to prevent the passage of air, means for bringing widened portions of said grooves adjacent the respective nozzles individually and successively to control the passage of air between said rollers and the respective nozzles, and means on said rollers for simultaneously actuating the valve with the air control of each nozzle.

4. A carbureter, comprising a fuel supply, a plurality of nozzles in communication therewith, a valve for each nozzle, a roller on each side of said nozzles provided with a groove closely fitting the respective nozzle to prevent the passage of air, said grooves being widened for a desired portion of their lengths, means for bringing the widened portions of each of said grooves adjacent each of said nozzles individually and successively to control the passage of air between said rollers and the respective nozzles, one of said rollers being provided with a cam for actuating each of said valves simultaneously with the movement of the air control grooves thereof.

5. A carbureter, comprising a fuel supply, a plurality of nozzles in communication therewith, a valve for each nozzle, means for controlling said valves and said air supply means for each of said nozzles simultaneously and at successive periods, and supplemental means for actuating all of said valves simultaneously.

6. A carbureter, comprising a fuel supply, a plurality of nozzles in communication therewith, a valve for each nozzle, means for supplying air around each nozzle, means for controlling said valves and said air supply means for each of said nozzles simultaneously and at successive periods, a plate in operative connection with all of said valves, and means exterior of said carbureter for actuating said plate to actuate all of said valves simultaneously, irrespective of the positions of said first named valve controls and said air supply controls.

7. A carbureter, comprising a fuel supply, a plurality of nozzles in combination therewith, a valve for each nozzle, means for supplying air around each nozzle, means for simultaneously actuating the valve of each nozzle and the air supply means thereof, individually, a lever in pivotal connection with each valve, a support for each end

thereof, and a plate in pivotal connection with all of said levers, said plate serving as the fulcrums for all of said levers in the operation of the individual valve control means, and one of said supports serving as the fulcrum of each lever for the simultaneous actuation of all of said levers by said plate, to control said valves collectively.

8. A carbureter, comprising a fuel supply, a plurality of nozzles in combination therewith, a valve for each nozzle, means for supplying air around each nozzle, means for controlling said valves and said air sup-

ply means for each of said nozzles simultaneously and at successive periods, supplemental means for actuating all of said valves simultaneously, and a thermometer for gaging the degree of adjustment of said supplemental valve actuating means.

In testimony whereof I have signed my name to this specification in the presence of two subscribing witnesses.

HARRY CARROLL MERRIAM.
